UNITED STATES PATENT OFFICE.

FERDINAND SCHMIDT, OF DES MOINES, IOWA.

DESIGN FOR A COVERED DISH OR SIMILAR ARTICLE.

Application filed December 9, 1922. Serial No. 4,559. Term of patent 7 years.

To all whom it may concern:

Be it known that I, FERDINAND SCHMIDT, a citizen of the United States, residing at Des Moines, in the county of Polk, State of Iowa, have invented a new, original, and ornamental Design for a Covered Dish or Similar Article, of which the following is a specification, reference being had to the accompanying drawing, forming part thereof.

In the drawings—

Fig. 1 is a front elevation of a dish embodying my invention.

Fig. 2 is a top view of the dish and

Fig. 3 is a section through a portion of the dish showing the manner in which the paneled characteristic of the design is produced.

The dish is subdivided into a plurality of similar panels by the raised ribs which gradually diminish in height.

I claim:

A design for a covered dish or similar article substantially as shown.

FERDINAND SCHMIDT.
